ULTRA HIGH FREQUENCY DEVICE

David Gordon Clifford, Palo Alto, Calif., and Ilia E. Mouromtseff, Montclair, N. J., assignors to Westinghouse Electric Corporation, East Pittsburgh, Pa., a corporation of Pennsylvania

Application December 29, 1942, Serial No. 470,490

4 Claims. (Cl. 250—27.5)

1

This invention relates generally to ultra high frequency devices and more particularly to such devices identified as diodes used for purposes of rectification of ultra high frequency oscillation or production of lower frequency oscillations by means of so called heat frequencies obtained by the introduction of other ultra high frequency oscillations of suitable frequency.

Considerable attention is being given at the present time to use of diodes as detectors in ultra high frequency service to replace crystal detectors. A structural premise of present-day diodes resides in the necessary close spacing of the diode electrodes, their separation being as little as practically possible and in practice amounting to but a few thousandths of an inch. Thus one difficulty encountered in the prior art has been to adequately reduce the spacing and maintain an even spacing of so small an amount without a contact inadvertently occurring and short circuit resulting.

In considering the incorporation of a resonant cavity as an integral part of a diode as above characterized, and wherein the electrodes of the diode are reentrant into the resonant cavity, the problem of tuning without disturbing the electrode spacing has heretofore eluded adequate solution. The necessity of avoiding contact of the electrodes referred to above is a more serious problem when one of the electrodes has to be moved for tuning purposes than when both are permanently fixed. A further difficulty is also introduced, in that heretofore a shifting of one electrode for tuning purposes not only changed the capacitative relation of the electrodes, but altered the electrode spacing and transit time of the electrons, which was highly detrimental.

When utilizing a resonant cavity for ultra high frequency oscillations, the interior or cavity wall constitutes a conductive surface for high frequency current. Continuity of that surface is desirable with minimum of interruption. Inasmuch, however, as part of the surface is connected with the anode and another part with the cathode, and anode and cathode have to be at different D. C. potentials, a discontinuity meeting this circumstance follows of necessity. The problem therefore presents itself of providing a structure of resonator which has a discontinuity effective to maintain difference of D. C. potential without materially interfering with the continuity for high frequency current flow.

The present invention accordingly has for its general object the provision of an improved, ef-

2

fective and efficient ultra high frequency device characterized as a cavity resonator detector.

Likewise, from a general aspect, an object of the invention is to overcome the difficulties enumerated above and to materially improve prior art constructions of ultra high frequency devices and especially diodes.

More specifically an object of the invention is to provide an ultra high frequency device as characterized wherein tuning is obtained while the electron emission and reception characteristics remain the same.

Of analogous nature is another object which the invention seeks to accomplish, namely, that capacitative variation may be accomplished without disturbing the relation of the emission effect between the diode electrodes.

Another object of the invention is to obtain mechanical rigidity of an electrode notwithstanding movability thereof for tuning purposes.

A further object of the invention is to permit substantially unimpaired H. F. current flow on the interior or cavity wall while maintaining a discontinuity in the wall for other purposes.

Still further objects of the invention will appear as the description progresses, both by direct recitation thereof and by implication from the context.

Referring to the accompanying drawing in which like numerals of reference indicate similar parts throughout the several views;

Figure 1 is a vertical sectional view of an ultra high frequency device constituted as a diode detector.

Figure 2 is a cross-section on line II—II of Fig. 1.

Figure 3 is an enlargement of that part of Fig. 1 showing the structural assembly by which effective discontinuity is obtained as to D. C. potential but with the effect of electrical continuity in regards to the H. F. current; and

Figure 4 is a view similar to Fig. 3 showing a modified construction.

In the specific embodiment of the invention illustrated in said drawing, the reference numeral 10 designates a sealed envelope, shown as of glass, with a reentrant glass stem 11 therein from which projects a metallic collar 12 flared at its upper end to provide a flange 13 in a plane transverse to the said collar. Above the collar and flange is a tubular cathode 14 the upper end of which is closed, as by integral end 15, and the lower end of which has a wide flange 16 projecting radially considerably beyond the flange 13 of the said collar 12. The cathode flange 16

rests flatwise on the collar flange 13, coaxial therewith and secured thereto as by welding or otherwise. Within the cathode 14 is a suitable heater 17 here illustrated as a coiled filament attached to appropriate lead-in wires 18 sealed through stem 11.

Coaxial with the cathode 14 is an anode 19 the lower part of which is hollow to provide a skirt portion 20 which girdles the upper end portion of the cathode in desired closely spaced relation thereto for obtaining the desired short transit time of electron path from cathode to anode. The cathode is indicated as having an emissive oxide coating 21 on the cylindrical portion thereof engirdled by the anode. Particular attention is called to the fact that emission from the cathode is preferably restricted to the region included between the cylindrical walls of the cathode and skirt portion of the anode.

The region within which cathode 14 and skirt portion 20 of anode 19 are located, is constructed as a resonant chamber 22 the walls of which are metal. The specific construction involved provides a cylindrical outer side wall 23, preferably of copper, coaxial with the cathode and anode and having its lower margin feather-edged and sealed to the glass portion of the envelope and thereby constituting a part of the said envelope.

The upper part of said side wall 23 is provided with an inner shoulder 24 for properly locating and supporting the rim or edge of a transverse flexible metallic diaphragm 25. The body portion of anode 19 projects through the middle of said diaphragm, and said diaphragm is vacuum sealed both to the anode and to said outer wall. By virtue of the resilient flexibility of the diaphragm, the length of the chamber may be varied as well as a change being obtained in capacity between anode and cathode, and thereby permits desired tuning of the same.

Both for tuning purposes and for accurate rigid mounting of the anode, the upper end of the anode is shown of sturdy construction and carried by an equally sturdy cap 26 in turn supported at its outer margin from the side wall 23 of the resonator chamber. The structure illustrated includes a ring 27 brazed or otherwise secured on the exterior of said wall 23 next the upper edge thereof and threaded on its outer surface to inter-engage with threads 28 on the inside of a skirt portion of said cap 26. Similarly the upper end of anode 19 provides a stem threaded at 29 engaging cooperating threads in the cap. In both instances the threaded engagements are adequately extensive to obtain and maintain accurate position of the anode skirt in its spacing around the cathode. Furthermore the threads 29 of the anode have a different pitch or otherwise rendered differential with respect to the threads on the outer wall so that rotation of the cap obtains longitudinal movement of the anode. By utilizing right-hand threads, for instance, in both places but of different pitch, a considerable rotation of the cap is required for a small longitudinal movement of the anode, thereby obtaining a fine tuning adjustment.

It will be understood by those versed in the art that a D. C. potential is established from any suitable external source between cathode 14 and anode 19 for obtaining electron transit from the one to the other. This necessitates electrical discontinuity between the cathode flange and the resonator side wall. The structure shown consists in providing a pair of headers, one above and the other below said flange and separated

therefrom by mica or other dielectric 30. While the headers have peripheral cylindrical portions 31 for welding or otherwise securing the same to the outer wall 23 of the resonant chamber, the part of primary importance is the plate or washer-like body portion 32 of the inner header overlapping in part the peripheral margin of the flange 16 from the cathode which projects between the similar plates of both headers. The intervening dielectric obtains the desired electrical discontinuity for the D. C. potential.

In order to obtain electrical continuity for the H. F. current across the area of D. C. discontinuity, the overlapping of flange 16 with plate 32 is made radially a quarter wave length in dielectric 30 referred to the generated wave of oscillations in the resonant chamber. Wave length in dielectric 30 is shorter than in air or vacuum of the chamber. The construction accordingly sets up a high impedance at the outer periphery of flange 16 which reflects a low impedance at the inner peripheral edge of plate 32 thereby presenting the effect of electrical continuity across the gap between flange and plate 32 at the inner periphery of the said plate.

For more definitely assuring the condition of high impedance at the periphery of the flange, a construction such as shown in Figure 4 may be employed. In this instance the headers are 30 constructed as before, but spaced apart somewhat farther to accommodate a different flange construction. Accordingly numeral 32 is again applied to the plate, but due to difference in the flange construction it is designated by numeral 35 16a. The overlap of flange 16a and plate 32 is, as before, a quarter wave length measured in the dielectric 30a intervening between the overlapping portions. At the underside of the flange is an impedance section comprised of an open annular cavity 30b between the under side of a part of said flange and a parallel plate 30c the inner periphery of which is bent upwardly and secured, by welding or otherwise to said flange, the upwardly bent portion 30d forming an inner end wall for the annular cavity 30b. The outer periphery of the parallel plate 30c turns upward beyond the end of flange 16a, as at 30e with a gap 30f between the said up-turned end 30e and end of flange 16a. Part of dielectric 30a closes the end of gap 30f and the parts are proportioned to establish substantially a free space quarter wave length distance from the said closed end 30d to the dielectric closure of gap 30f. The low impedance at closed end 30d will accordingly reflect a high impedance at gap 30f, as desired, and accordingly insures a high impedance at the periphery of flange 16a to insure, in turn, a low impedance at the inner periphery of plate 32. It may be further added that the dielectric, such as mica, fills the region beyond upturned end or rim 30e and the wall 23 of the resonant chamber, as well as the space between the lower header and the cavity-forming under plate 30c. A few holes or slots 30g may be provided from the evacuated chamber into annular cavity 30b for enabling that cavity likewise to be evacuated.

In practice, the device is evacuated through the stem, as by tubulation opening 33 therein, there being suitable slots 34 in the collar 12 and slots 35 in flange 16 or 16a to accomplish complete outgassing so that resonant chamber 22 will function in vacuum. Oscillations set up in said chamber may be transferred for useful purpose by a usual output means, such as concentric line and loop 36 shown.

It may now be particularly pointed out that by proper choice of dimensions of the several parts, the spacing of cathode and anode can be very small, limited only by mechanical considerations, thus making possible a time of transit in this diode consistent with satisfactory operation at ultra high frequencies. The change in the lumped capacity of the device due to movement of the anode 19 with diaphragm 25, with corresponding change of frequency for tuning purposes, does not affect the transit time of electrons between cathode and anode. Likewise the dielectric spacing of flange and plates with impedance control between the cathode and outer wall provides an efficient means for obtaining a high frequency rectified current or beat frequency.

While arbitrarily selected exemplifications of the invention have been herein shown, it is to be understood that this has been done through necessity of presenting a physical embodiment of the invention and it therefore follows that all matter contained in the specification or depicted in the drawing shall be interpreted as illustrative and not necessarily in a limiting sense, and as setting forth the true scope of invention by statements of both the generic and specific features thereof which as a matter of language encompass the inventive concept.

We claim:

1. An ultra high frequency device comprising electrodes of which one is a cylindrical cathode and another is an anode having a cylindrical skirt portion telescopically overlapping an end of the cathode, said cathode having an emissive portion and a non-emissive capacitative portion in continuation of the emissive portion and the emissive portion being at the said end overlapped by the cylindrical skirt portion of the anode, said skirt portion being radially opposite the entire emissive portion of the cathode, and the non-emissive portion of the cathode projecting from said skirt, an enclosure around said electrodes, and movable means extending from said enclosure to one of said electrodes for adjusting the telescopic overlap of said electrodes longitudi-

nally and thereby varying the inter-electrode capacity while maintaining constant electron-path spacing between said electrodes.

2. An ultra high frequency device comprising a diode structure having a cathode and anode and evacuated enclosure therefor, said cathode and anode overlapping and having a constant radial spacing for the electron path therebetween and telescopically adjustable as to distance of overlap for varying inter-electrode capacity thereat, and means other than said spacing establishing direct current discontinuity in the enclosure between the cathode and anode comprising parts insulated from each other and overlapping an odd quarter wave-length distance and establishing thereat an effect of negligible impedance to high frequency current and establishing effect of electrical continuity to high frequency current.
3. An ultra high frequency device comprising a metallic enclosure forming a resonator, a cathode and an anode each within said resonator, and an impedance section within said enclosure comprising parts insulated from each other and overlapping an odd quarter wave-length distance, said cathode being connected with one of said overlapping parts of the impedance section and said anode being connected with another of said overlapping parts of the impedance section, whereby said impedance section establishes a direct current discontinuity between the cathode and anode and establishes thereat an effect of negligible impedance to high frequency current and establishes effect of electrical continuity for high frequency current.
4. An ultra high frequency device comprising a metallic enclosure forming a resonator, a cathode and an anode in said resonator, said cathode having a flange projecting laterally therefrom and said enclosure having a plate overlapping said flange a distance substantially equal to a quarter wave-length in dielectric, and dielectric between said overlapping plate and flange.
